REFRIGERATOR CABINET

Daniel B. Dawley, Anchorage, Ky., assignor to General Electric Company, a corporation of New York
Filed Dec. 21, 1964, Ser. No. 419,861
3 Claims. (Cl. 312—213)

The present invention relates to refrigerator cabinets of the type including a machinery compartment at the bottom thereof and has as its principal object the provision of an improved grille and grille mounting means for closing the vent opening to the machinery compartment.

Many household refrigerators including a machinery compartment at the bottom portion thereof also includes a drain pan in the machinery compartment for receiving and disposing of defrost moisture from the refrigerated compartment or compartments. In order that the drain pan can be periodically cleaned, some means must be provided for ready access to the machinery compartment and to that end there is provided an access opening in the front wall of the refrigerator cabinet and a removable decorative grille for normally covering this access opening. As this grille extends forwardly from the face of the cabinet, it and its support must be strong enough to support a person's weight without being displaced or damaged in the event the user accidentally or intentionally steps on the grille.

A primary object of the present invention is to provide an improved grille and grille supporting arrangement meeting the above requirements.

Further objects and advantages of the invention will become apparent as the following description proceeds and the features of novelty which characterize the invention will be pointed out with particularity in the claims annexed to and forming part of this specification.

In accordance with the present invention there is provided a refrigerator cabinet including a machinery compartment in the lower portion thereof and an access opening to the machinery compartment extending along the front of the cabinet. For closing the access opening to the machinery compartment, there is provided a grille of a generally box-like structure including end walls and support means for removably supporting the grille on the cabinet. The support means includes a pair of sheet metal brackets, one at each end of the access opening, and each of these brackets includes one leg overlying and secured to the wall of the cabinet and a second leg which projects forwardly from the first leg and which preferably is tapered so that at least the lower edge thereof is inclined. Upper and lower projections provided on the opposed end walls of the grille are designed respectively to be received in upper and lower grooves provided in each of the brackets when the grille is mounted on the cabinet. A generally horizontal slot in the forwardly extending bracket leg divides this leg into a relatively rigid upper portion of a strength sufficient to support the grille and the weight of a person standing on the grille and a spring-like lower portion which is sufficiently resilient to permit the lower projections to be mounted in the respective lower grooves and which applies a downward force on the lower projections sufficient to firmly anchor the upper projections in their mating grooves when the grille is assembled on the cabinet. By this arrangement, the lower spring-like portions of the brackets provide a spring-like anchoring and release means permitting the grille to be removed from or replaced on the cabinet wall while the upper portion of the brackets provide all of the strength necessary for supporting the grille and any normal weight placed thereon.

2

For a better understanding of the invention reference may be had to the accompanying drawing in which:

FIGURE 1 is a sectional view of a lower portion of a refrigerator cabinet;

5 FIGURE 2 is a detailed perspective view of a portion of the grille and grille mounting arrangement of the present invention;

FIGURE 3 illustrates a second embodiment of the present invention; and

10 FIGURE 4 illustrates another embodiment of the invention.

With the reference to FIGURE 1 of the drawing, there is shown a refrigerator cabinet including a refrigerated storage compartment 1 and a door 2 for closing the access opening to the compartment 1. A machinery compartment 3 provided in the lower portion of the cabinet and separated from the food storage compartment by means of an insulated partition 4 has an access opening 5 at the front thereof which is closed by a grille 6.

15 20 A drain and evaporating pan 7 positioned within the machinery compartment 3 in heating relationship with the condensing unit 8 is positioned to receive defrost water flowing from the storage compartment 1 through a drain tube 9 in the partition 4.

25 25 The grille 6 for closing the access opening 5 in the front wall 10 of the cabinet is of a generally box-like structure including a front wall 12 having vents 14 therein, a top wall 15 and opposed end walls 17, only one of which is shown.

30 30 In the embodiment of the invention illustrated particularly in FIGURE 2 of the drawing, a grille mounting and support means comprises a sheet metal bracket generally indicated by the numeral 18 and including a first leg or flange 19 secured as by means of screws or bolts 20 to the face 10 of the cabinet on opposite ends of the access opening 5 and an angularly or forwardly extending leg or flange 21 projecting forwardly from the face of the cabinet within the box-like grille 6. A slit 22 extending generally horizontally from the forward edge of the leg 21 entirely through this leg, and preferably part way into the leg 19, divides the leg 21 into a rigid upper portion 23 and a resilient or spring-like lower portion 24. Preferably both the upper and lower edges of the bracket leg 21 are inclined respectively downwardly and upwardly so that the leg 21 as is more clearly illustrated in FIGURE 4 of the drawing tapers forwardly.

40 45 An upper groove 26 in the upper edge of the bracket and a lower groove 27 in the lower edge of the spring-like portion 24 of the bracket are designed respectively to receive an upper projecting means 28 and a lower projecting means 29 secured to the end wall 17 of the grille for firmly supporting the grille 6 on the face of the cabinet.

50 55 In the embodiment of the invention illustrated in FIGURE 2, the projections 28 and 29 form part of the U-shaped rod positioned or contained within the box-like grille and having its base portion 30 suitably secured as by means of welding or brazing to the inner surface 60 of an end wall 17. The projections 28 and 29 extend inwardly in a plane which is generally parallel to the base 10 of the cabinet when the grille is positioned on the cabinet or in other words in a direction generally perpendicular to the plane of the bracket leg 23.

65 70 65 In mounting the grille on the cabinet it is only necessary to place the grille in front of the cabinet and position the upper projections 28 in their respective grooves 26. By a downward tilting movement of the grille, the lower projections 29 are moved downwardly along the sloping lower edges of the portions 24, the resiliency of the lower portions 24 of the bracket causing these por-

tions to spring upwardly a sufficient distance so that the lower projections 29 can be moved into position within the lower grooves 27 and against the shoulders 30 forming the rear wall of these grooves.

The downward biasing force of the spring-like portions 24 bearing against the lower projections 29 firmly anchors the upper projections 28 in their supporting grooves. For removal of the grille, it is merely necessary to grasp the lower edge thereof and with an outward tilting movement cause the projections 29 to slide free of the respective grooves 27 after which the grille can be moved forwardly to a position in which the projections 29 clear the lower portions 24.

In the embodiment of the invention illustrated in FIGURE 3 the support projections on the grille end wall 17 are in the form of rods or studs 31 and 32 rigidly secured to a base plate 33 which in turn is secured by bracing or welding to the end wall 17. The studs 31 and 32 are spaced from one another a distance such that as to be firmly and securely received in the upper 20 and lower grooves 26 and 27.

In the embodiment of the invention illustrated in FIGURE 4 of the drawing, the grille 6 is provided with end walls indicated by the numeral 35 of sheet metal or suitable plastic material formed to include as an integral 25 part thereof upper and lower projections 36 and 37 designed to be received in the upper and lower grooves 26 and 27 and to function in the same manner as the projecting means 28 and 29.

From the above description, it will be seen that there has been provided a grille and grille support means of simple, low cost construction. The grille will support any normal or abnormal weights or forces placed thereon and yet can easily be removed and reassembled on the cabinet front wall. In addition and particularly in the case of the embodiments of the invention illustrated in FIGURES 2 and 3 of the drawing, the grille mounting design allows a wide variation in cabinet widths and bracket spacing without affecting the performance of the supporting means.

While there has been shown and described specific embodiments of the present invention, it is to be understood that the invention is not limited thereto and it is intended by the appended claims to cover all such modifications as fall within the true spirit and scope of the invention.

What I claim as new and desire to secure by Letters Patent of the United States is:

1. In a refrigerator cabinet including a machinery compartment, a wall including an access opening to said compartment and a grille including end walls covering said opening, means for removably supporting said grille on said cabinet comprising:
a sheet metal bracket connected to said wall at each end of said opening,
each of said brackets including a leg projecting forwardly from said wall,
said leg including upper and lower edges, each having a groove therein,
upper and lower projecting means on said grille end walls adapted to be received in said grooves when said grille is mounted on said cabinet,
said leg also including a slit extending rearwardly from the forward end thereof and spaced from said lower edge of said leg to divide said leg into a rigid upper portion for supporting said grille and a spring-like lower portion adapted to be resiliently displaced as the lower projecting means is snapped into position in said lower edge groove and to exert thereon

5
10

4
a downward force anchoring said upper projecting means in said upper edge groove.

2. In a refrigerator cabinet including a machinery compartment, a front wall including an access opening to said compartment and a grille including end walls covering said opening, means for removably supporting said grille on said cabinet comprising:

sheet metal brackets respectively connected to said front wall at opposite ends of said opening,
each of said brackets including one leg overlying and secured to said cabinet and a second leg projecting forwardly from said first leg,
said second leg being tapered forwardly and including a downwardly inclined upper edge and an upwardly inclined lower edge,
each of said edges having a groove therein,
upper and lower projecting means on said grille adapted to be received in said grooves when said grille is mounted on said cabinet,
each of said brackets including a slit extending rearwardly from the forward edge of said second leg and part way into said first leg,
said slit being spaced from said lower edge of said bracket to divide said bracket into a rigid upper portion and a spring-like lower portion, said projecting means being spaced a distance such that when said grille is mounted on said cabinet said lower portion exerts on the said lower projecting means a downward force serving to anchor said upper projecting means in said upper edge groove.

3. In a refrigerator cabinet including a machinery compartment, a front wall including an access opening to said compartment and a grille including end walls covering said opening, means for removably supporting said grille on said cabinet comprising:

sheet metal brackets respectively connected to said wall at opposite ends of said opening,
each of said brackets including one leg overlying and secured to said wall and a second leg projecting forwardly from said first leg,
said second leg being tapered forwardly and including a downwardly inclined upper edge and an upwardly inclined lower edge,
each of said edges having a vertical groove therein,
upper and lower projecting means on each of said grille end walls adapted to be received respectively in said grooves in said upper and lower edges when said grille is mounted on said cabinet,
each of said brackets including a slit extending rearwardly from the forward edge of said second leg and part way into said first leg,
said slit being spaced from said lower edge of said bracket to divide said bracket into a rigid upper portion and a spring-like lower portion whereby said lower portion can be resiliently displaced to permit the lower projecting means to be snapped over the lower inclined edge of said bracket and into the groove therein upon mounting movement of said grille in the direction of said front wall.
